UNITED STATES PATENT OFFICE.

FRED B. HUNTINGTON, OF COSMOPOLIS, WASHINGTON.

FEED MECHANISM FOR SHINGLE-MACHINES.

1,149,058.

Specification of Letters Patent.

Patented Aug. 3, 1915.

Application filed October 29, 1914. Serial No. 869,299.

To all whom it may concern:

Be it known that I, FRED B. HUNTINGTON, a citizen of the United States, residing at Cosmopolis, in the county of Chehalis and 5 State of Washington, have invented certain new and useful Improvements in Feed Mechanisms for Shingle-Machines, of which the following is a specification, reference being had to the accompanying drawings.

10 My invention relates to new and useful improvements in feed mechanism adapted for use with a shingle machine of the type shown in Letters Patent No. 885,327, granted April 21, 1908, to "The Sumner Iron 15 Works, of Everett, Washington", although the mechanism may be adapted for use with other machines.

The primary object of my invention is to provide an automatic self-locking ratchet 20 feed mechanism capable of fine and accurate adjustment and having a wide range for adjustment without removal from the machine, the parts being capable of being quickly adjusted and the mechanism being 25 extremely simple in construction.

With these objects in view my invention consists in the details of construction and arrangement hereinafter more fully described.

30 In order that those skilled in the art to which my invention appertains may know how to make and use my improved mechanism, I will now proceed to describe the same, referring by numerals to the accompanying drawings, in which—

Figure 1 is a diagrammatic view showing the relation of the feed mechanism with a shingle machine, the latter shown in broken lines; Fig. 2 is an end elevation of the feed 40 mechanism and feed rollers; Fig. 3 is a vertical section of feed mechanism and its casing on the line *a—a* of Fig. 2, the broken lines showing the direction of the tilt or vibration; Fig. 4 is a horizontal section on the 45 line *b—b* of Fig. 1.

Referring to these drawings, wherein similar reference numerals indicate like parts, 1 designates a ratchet wheel having formed therewith a pinion 2 whose plane is 50 offset from the plane of the ratchet teeth. Intermeshing with the pinion 2 is a toothed gear 3, and coacting with the ratchet teeth is a pawl or dog 4, all of these parts being inclosed within a suitably shaped casing 5. 55 The gear 3 is formed with an elongated hub 6 extending through and slightly beyond the

casing 5 on both sides of the casing, and this hollow hub 6 being mounted upon the shaft 11, forms the pivotal axis for the casing 5. The hub 6 at one end is formed with a diametrically extending slot 7 and at the other end with a diametrically extending slot 9. Either one of these slots is adapted to receive a pin 10 whereby the gear may be pinned to the shaft to turn therewith. The 60 object of having the diametrical slots in opposite ends of the hub is to permit the casing 5 to be reversed in its position upon the hub 6 so that the same mechanism may be used for the upper feed and for the lower 65 feed, as will be later stated. A nut 12 fits upon the end of the shaft 11 and holds the casing rigidly in place.

The shaft 11 carries a plurality of feed 70 rollers 14 adapted to engage a block from which shingles are to be sawed. Therefore, when this shaft 11 is rotated in the direction of the arrow in Fig. 3, if the feed rollers engage the upper face of the block, or in a direction reverse to the arrow if the feed rollers are designed to engage the lower face of the block, the feed rollers will be actuated to feed the shingle block forward to permit the shingle to be cut from the end thereof in a manner well known in the art and fully 80 illustrated in the patent before referred to.

Referring to Fig. 1, it will be seen that there are two sets of feed rollers, one above the block and one below the block, and that these feed rollers must move in reverse directions. Each set of feed rollers is of course actuated by the mechanism shown in Fig. 3, the mechanism, however, for the two feed rollers being reversed relative to each other. Each casing 5 is oscillated upon its axial 90 center by an arm 15 which is pivotally connected at 16 to the casing, and at the other end is pivotally connected to one arm of a bell crank lever 17 mounted upon the framework of the machine, as illustrated in Fig. 1. 95 The inwardly directed arm of each bell crank lever carries upon it a roller 18, and the extent of oscillation of each bell crank lever is controlled by an adjusting screw 19 mounted in a suitable bracket 20 secured upon the 100 frame of the machine. I have illustrated these adjusting screws for this purpose, but it will be understood that other means might be used if desired.

The normal position of each casing is that 110 shown in dotted lines in Fig. 1. When one shingle has been sawed from the block, cer-

tain cams designated 21 and illustrated diagrammatically in dotted lines in Fig. 1, engage the rollers 18 and cause the bell crank lever to shift, thus tilting each casing from the position shown in dotted lines to the position shown in full lines. Assuming now that Fig. 3 is a view of the lowermost feed device, the normal position of which is shown in dotted lines in Fig. 1, then upon 5 the corresponding bell crank lever being oscillated by contact of the roller 18 with the cam 21, the rod 15 will be shifted in the direction of the arrow *a*, Fig. 3. This will carry the casing in the same direction around 10 the axis formed by the shaft 11. This would cause the gear 2 to rotate in the direction of the arrow *c* were it not that the gear is prevented from rotation by the pawl 4. The gear 2 being held from rotation by the pawl 15 15 20 25 30 35 40 45 50 55 60 65

4, the gears 2 and 3 will be locked and the shaft 11 will as a consequence be rotated in a clockwise direction. Upon a reverse movement, however, the gear 2 will rotate upon the gear 3 in a counter-clockwise direction, the teeth of the ratchet 1 slipping by the pawl 4. The amount of rotation will of course depend on the length of the stroke of the rod 15 and this length of stroke is regulated by the adjusting screw 19. The operation is the same for the upper feed mechanism except that in this upper feed mechanism the pawl 4 extends in the direction opposite to that shown in Fig. 3 and the teeth of the ratchet wheel 1 also extend 55 in an opposite direction, so that a pull upon the rod 15 will cause the rotation of the shaft 11 connected thereto in a counter-clockwise direction and the gear wheel 2 will run idle upon the gear 3 upon an outward movement of the rod 15. Thus the block will be fed outward into position for a new cut.

It will be understood of course, that in this type of machine the feeding devices are mounted upon a sliding carriage and that the cams 21 are relatively fixedly mounted with relation to the carriage. These cams will engage with the rollers 18 to cause the feeding forward of the block. 45 50 55 60 65

The objection to the feed mechanism described in the patent heretofore referred to and used on machines manufactured under this patent is that the feed is too coarse and cannot be finely and accurately adjusted because the adjusting screws must be set with relation to the space between the ratchet teeth. It is obvious that with my mechanism the fineness of the adjustment is controlled by the size of the teeth on the ratchet 115 120 125 130

60 65

and by the ratio between the pinion gear and the toothed gear wheel, this ratio in the drawings being 1 to 3. As the feed mechanism is inclosed within the casing it cannot become clogged with dirt and sawdust, nor are there any projecting parts to catch in

the clothes of the operator and act to impede the operation of the ratchet mechanism.

Having described my invention, what I claim is:

1. In a mechanism of the character described, a shaft, a toothed gear wheel mounted thereon and fixed thereto, a pinion wheel meshing with the toothed gear wheel, and having peripheral ratchet teeth, a supporting member pivotally mounted on the shaft and rotatably supporting said pinion, a pawl carried by the supporting member and engaging the ratchet teeth of the pinion, and means for oscillating said supporting member. 70 75 80

2. In a mechanism of the character described, a shaft, a toothed gear wheel mounted thereon for rotation therewith, a supporting member mounted upon the shaft as an axis, a pinion carried by said supporting member and meshing with the toothed gear wheel, means carried by the supporting member permitting a rotation of the pinion in one direction but preventing its rotation in the other direction, and means for oscillating said supporting member. 85 90

3. In a mechanism of the character described, a shaft, a toothed gear wheel mounted thereon for rotation therewith, a supporting member mounted upon the shaft as an axis, a pinion carried by said supporting member and meshing with the toothed gear wheel, means carried by the supporting member permitting a rotation of the pinion in one direction but preventing its rotation 95 100 105 in the other direction, and means for oscillating said supporting member, said means including a bell crank lever and a member engageable with the bell crank lever to oscillate it.

4. In a mechanism of the character described, a shaft, a toothed gear wheel mounted upon the shaft, a supporting member rotatably mounted upon the shaft, a pinion carried by the supporting member and meshing with the toothed gear wheel, means preventing a rotation of the pinion in one direction but permitting a rotation in the other direction, a bell crank lever having a connection between one of the arms of the lever and the supporting member, means for shifting the bell crank lever to thereby oscillate the supporting member to cause the rotation of the shaft, and adjustable means for limiting the length of movement of the bell crank lever. 110 115 120

5. In a mechanism of the character described, a shaft, a member oscillatable on the shaft, a pawl carried by the member, a ratchet wheel also carried by the member and with which the pawl engages, and gear wheels operatively engaging the shaft with said ratchet wheel, said shaft being locked to the member for common movement therewith by said pawl upon a movement of the 125 130

member in one direction but unlocked therefrom upon a movement in the opposite direction.

6. In a mechanism of the character described, a shaft, a member oscillatable on the shaft, a pawl carried by the member, a ratchet wheel carried by said member and with which the pawl engages, and gear wheels freely rotatable in engagement with each other upon a movement of the member in a direction to carry the pawl over the ratchet teeth but locked from independent rotation with each other upon a common movement of the member, ratchet wheel, and pawl.

7. In a mechanism of the character described, a shaft, a member movable concentric thereto, a wheel carried by said member, means for locking the wheel to the said member upon a movement of the member in one direction, said means releasing the wheel upon a movement in the opposite di-

rection, and gear wheels disposed between said wheel and shaft operatively engaging them with each other.

8. In a mechanism of the character described, a shaft, a casing oscillatable upon the shaft, a pawl carried by and within said casing, a ratchet wheel rotatably mounted in said casing and with which the pawl engages, and gear wheels disposed within the casing operatively engaging the shaft with said ratchet wheel, said shaft being locked to the casing by said pawl upon a movement of the casing in one direction and unlocked therefrom upon a movement in the opposite direction.

In testimony whereof I hereunto affix my signature in the presence of two witnesses.

FRED B. HUNTINGTON.
